UNITED STATES PATENT OFFICE.

HENRY LEHR AND CHARLES VERCH, OF ALBANY, NEW YORK.

CAR-COUPING.

SPECIFICATION forming part of Letters Patent No. 358,617, dated March 1, 1887.

Application filed October 15, 1886. Serial No. 216,331. (No model.)

To all whom it may concern:

Be it known that we, HENRY LEHR and CHARLES VERCH, of Albany, in the county of Albany and State of New York, have invented 5 a new and Improved Car-Coupling, of which the following is a full, clear, and exact description.

Our invention relates to car-couplings, and has for its object to provide a simple, inexpensive, and durable coupling which will automatically couple two cars as they come together, and may readily be uncoupled, and may be adjusted at will to prevent coupling, and all without requiring the train-men to go 15 between the cars and expose themselves to injury.

The invention consists in certain novel features of construction and combination of parts of the car-coupling, all as hereinafter fully 20 described and claimed.

Reference is to be had to the accompanying drawings, forming a part of this specification, in which similar letters of reference indicate corresponding parts in all the figures.

25 Figure 1 is a longitudinal vertical sectional elevation of part of a car and one of our improved couplings attached thereto, and a side elevation of part of an opposing car-coupling, and in positions just prior to coupling the 30 opposing cars. Fig. 2 is a detail sectional elevation of the forward part of one of the couplings with an ordinary link and pin, indicated in dotted lines. Fig. 3 is a plan view of an end part of a car, partly broken away near 35 each side, and with our improved coupling applied thereto. Fig. 4 is a front end view of the parts shown in Fig. 3. Fig. 5 is a perspective view of the coupling draw-head. Fig. 6 is a side elevation of the forward ends of two 40 couplings in coupled condition, and Fig. 7 is a side view of the renewable draft-pin of the coupling.

The draw-head A of our coupling is supported to slide longitudinally in a strap, B, 45 fixed to the car frame or body C, and is arranged with a draw-bar, D, and buffer-spring E, in the usual or any approved way. The draw-head has an ordinary link-receiving socket, a, and a vertically-ranging hole, a', allowing a common link, F, to be held in the

socket a by a pin, G, passed into the hole a', and as indicated in dotted lines in Fig. 2 of the drawings, and whereby cars having the common link-and-pin draw-head may be coupled to cars provided with our coupling. 55 The forward part of the draw-head A around the flaring-mouth of the link-socket a is made solid and quite heavy, (see Fig. 2,) to successfully withstand the shocks of contact in coupling opposing cars prior to the meeting of the 60 dead-blocks c c of the cars.

In a horizontally-ranging hole of the draw-head A there is fitted a pin, H, which has an inwardly-tapering collar, h, fitting a countersink in one side of the draw-head around the 65 hole through which the pin passes, and at its other end the pin H is flattened at one or more of its sides, as at h', and on this part h' there is fitted snugly the back end or eye, i, of a hook, I, which is held on the pin, preferably by a 70 washer, i', and a pin or cotter, J, passed through the pin H outside of the washer. The pin H thus will be held in the draw-head so it cannot move endwise, and will turn as the hook is swung down or up for coupling or uncoupling 75 cars, as presently explained. The coupling-pin H is provided outside of the collar h with a rounded part or neck, h², with which the head of a coupling-hook, I, of an opposing car is adapted to engage, and the pin H is 80 preferably provided with a head, h³, to prevent lateral displacement of the coupling-hook from the pin.

The coupling-hook I has at its back or lower end a short arm or stem, i², which, when the 85 hook is raised, as in Fig. 1, stands directly behind a push-pin, K, which is fitted to slide in a bearing or lug, k, on the side of the draw-head, and forces the push-pin out beyond the front face of the draw-head in position to be 90 struck by a lug, L, fixed to the side of a like opposing draw-head, for throwing the hook I down to engage the neck h² of the draft-pin H on the opposite draw-head for automatically coupling two cars as they come together. The 95 outer face of the lug L recedes from the front of the draw-head from the base to the top of the lug, and the top of the lug stands about opposite or a little above the center of the neck h² of the draft-pin H, and the draw-head 100

also has a lug, k' , which preferably is an upward extension of the trip-pin lug k , and onto which lug k' the front edge of the lowered hook I rests, and at such time the inwardly slanted or curved outer face, i^2 , of the hook will be held in position to strike the receding or inclined outer face of the lug L, and be thereby guided automatically up to and over the neck h^2 of the adjacent draft-pin H to drop behind the pin for coupling; hence the coupling of two cars provided with our couplings will be effected automatically as the cars come together, whether the hooks I, I of the cars be both raised or lowered, or whether either one of the hooks I be raised and the other hook be lowered, unless the hooks be held in raised positions by retaining devices, presently described, and which prevent falling of the hooks. Should the draft-pin H break off, the hooks I will catch onto the lugs L, which will be made strong enough to draw the cars by until new draft-pins can be put in place in the draw-heads, which may very readily be done.

We form a lateral depression, a^2 , in the side 25 of the draw-head A, just behind the projecting-neck h^2 of the draft-pin H and the lug L, for the purpose of allowing the inner face 30 of the head of the coupled hook to rock into said depression a^2 , to prevent lateral strains on the hook as the coupled cars are rounding 35 curves of the track, and also to allow two cars to be coupled by the hooks and uncoupled at will as they are standing on a curve. To facilitate these last-described operations, we cut 40 away or round over the inner face of the end bar of the hook I, as shown at i^4 in the drawings.

To the hook I, and preferable to a shackle, m, thereon, there is attached one end of a chain, 45 M, the other end of which is attached to an arm, N, which is fixed to a transverse shaft, O, journaled in bearings o' o', fixed to the end of the car-body. The ends o o of the shaft O are bent at right angles with the main part of 50 the shaft, and also at a right angle with the projecting arm N on the shaft, whereby on turning either of the crank-arms o o at either side of the cars the coupling-hooks I will be lifted from the draft-pins H of the opposing 55 draw-heads, to effect the uncoupling of the cars without requiring the train-men to go between the cars and expose themselves to injury.

To hold the coupling-hooks so that they will not be thrown down as the cars come together, 55 and thus prevent coupling of the cars as they are shunted, or kicked about the yard or on the tracks in making up trains or running cars onto sidings, we fit rods P into bearings p' p' on the car-bodies, and these rods each have an

arm, p, which may be moved in front of the hook I by sliding the rod P endwise, and as shown clearly in Figs. 3 and 4 of the drawings. The cars thus will not only couple automatically when the arms p of the rods P are withdrawn from in front of the hooks, and whether 65 the hooks, one or both of them, be raised or lowered, as above described, but the cars may, at will, be prevented from coupling, as circumstances may require.

It is not essential that the hook I be fitted 70 on the pin H to turn with the pin, as it may be fitted to turn freely on the pin; but the construction shown is preferred, as the hook then has little or no lateral play, due to the bearings the pin has in the draw-head, and the hook 75 will operate with certainty to engage the neck of the pin of the opposing draw-head.

Having thus described our invention, what we claim as new, and desire to secure by Letters Patent, is—

1. In a car-coupling, the combination, with a hook, as I, pivoted to the draw-head and adapted to engage a stud of an opposing draw-head, of a rod, P, having an arm, p, adapted for movement in front of the hook to hold it 85 raised to prevent coupling of the cars, substantially as shown and described.

2. In a car-coupling, a draw-head made with a pivoted hook, as I, having a stem, i^2 , a trip-pin, K, adapted to act on the stem i^2 to automatically lower the hook as the cars come together, a stop-lug, k' , limiting the fall of the hook, a stud, as h^2 , on the opposite side of the draw-head, and an inclined lug, L, next said stud h^2 , and up which lug the hook of an opposing car may ride to couple with the stud 95 automatically, substantially as shown and described.

3. In a car-coupling provided with a laterally-projecting stud, as h^2 , on its draw-head 100 adapted to be engaged by a hook on an opposing draw-head, said first-named draw-head provided with a lateral depression, a^2 , behind its stud h^2 , substantially as described, for the purposes set forth.

4. In a car-coupling, the draw-head provided with a laterally-projecting stud, as h^2 , and a lateral depression, a^2 , behind said stud, and a hook, I, pivoted at the opposite side of the draw-head and having a rounded inner 110 face, as i^4 , adapted to rock in a lateral depression of a like opposing draw-head, substantially as shown and described.
